UNITED STATES PATENT OFFICE.

JOSEPH ADOLPH GEORGE KIRSTEN, OF RANDFONTEIN, TRANSVAAL.

APPARATUS FOR SHARPENING ROCK-DRILLING-MACHINE BITS.

No. 812,570.

Specification of Letters Patent.

Patented Feb. 13, 1906.

Application filed March 15, 1905. Serial No. 250,151.

To all whom it may concern:

Be it known that I, JOSEPH ADOLPH GEORGE KIRSTEN, a subject of the King of Great Britain, residing at Randfontein, Transvaal, have 5 invented certain new and useful Improvements in Apparatus for Sharpening Rock-Drilling-Machine Bits and the Like, of which the following is a specification.

The improvements constituting the subject-matter of the present application have 10 reference to apparatus or machines intended for use in the sharpening of that class of rock-drilling-machine bit commonly known as the "star" bit. It may also be adapted to other 15 drills or bits of similar shape whether employed for hand or machine drilling.

The object of the present invention is to construct a machine of simple design in or by aid of which the drills or bits may be sharpened with expedition and precision.

In my improved machine the drill or bit is swaged to the correct size and shape—that is to say, the webs or wings are brought up to the required gage and the corners or tips of 25 the wings which are worn off when the drill or bit is in use are worked out of the steel of which the tool is made—and the radial cutting edges simultaneously formed along the edges of the wings at the cutting extremity 30 of the drill or bit.

I will at once proceed to describe my invention in detail by aid of the appended sheet of drawings, which illustrate a machine constructed in accordance therewith, and in 35 which—

Figure 1 represents a front elevation of the machine. Fig. 2 is a side elevation. Fig. 3 is a plan. Fig. 4 represents a front elevation of the several dies and the die holders or stops 40 drawn to an enlarged scale. Fig. 5 is a side elevation of one of the dies and its holder. Fig. 6 is a side part-sectional elevation of the dolly or tool for swaging the bit. Fig. 7 is an 45 end elevation of Fig. 6. Fig. 8 is an end elevation of the carriage which serves for supporting the shank or outer end of the drill during the operation of sharpening, showing also the bed and means for traversing the carriage longitudinally thereof; and Fig. 9 is an 50 elevation of the plate to provide for access to the dies, to which is affixed the rest for the front end of the drill.

In the drawings, 1 represents a vertical plate which is bolted or otherwise securely fixed to one end of a table or frame 2. The 55 table 2 comprises the side plates 3 4, which at one end are shaped to form the legs 5 and are at the other end fitted with the legs or supports 6 for carrying it at a convenient height. The plate 1 is bolted to the table 2 through 60 the angle-irons 7, which also strengthen the frame 2 and form supports.

In the front and at the top of the plate 1 is bolted or otherwise securely attached a plate 8. This plate 8 is shaped on the inside to 65 form four boxes or radial guideways 9, which in the drawings are shown formed between parallel ribs 10, formed on the back of the plate. A hole 11 is formed through the center of the plate 8, and a coincident hole 12 is 70 formed in a detachable plate 12^a, (see Fig. 9,) fixed to the back of the plate 1. The plate 12^a is provided to allow of access being obtained to the dies to facilitate the changing of the dies. The plate 12^a is fixed to the 75 plate 1 by the cleats 12^b. In the guideways 9 are arranged four stops or die-holders 13, which have attached to their inner ends the four dies 14. (See Fig. 4.) The die-holders 13 at their inner ends are formed with dovetailed recesses 15, and the dies 14 are formed with corresponding dovetailed projections 16, which fit into the dovetail recess 15 in the holders 13 and so secure the dies. The several dies 14 are shaped on the inside with V-shaped projections 17 at the center, (see Fig. 4,) which fit between the wings of the drill 1^a when the latter is placed in position between the dies 14. They are formed with a rounded or curved part 18, (see Fig. 4,) which corresponds with the outer end of the wing or web of the drill in such manner that when the several dies 14 are assembled or brought together they form between them the shape of the cutting end of the bit. As seen in Fig. 5 95 the curved parts 18 of the dies 14 are made parallel for a short distance, as is indicated at 19, and then incline inward, as indicated at 20, to form the taper on the wings of the drill in the direction of the shank. Dies are provided of similar construction to the above for operating upon the several standard sizes of drills.

The top vertical die D is adjustably held in

position by means of a bridle 21, which is fixed between the plates 1 8 at the top. Through the top of this bridle 21 is screwed a bolt 22, which is attached to the top die holder or stock 13. By raising or lowering the bolt 22 the top die 14 and its stock 13 may be raised or lowered in its guideway 9 to obtain any desired adjustment. Locking-nuts 23 24 are fitted on the bolt 22 above and below the bridle 21. The other three dies 14—that is to say, the lower vertical die 14 and the two horizontal dies 14—are adapted to reciprocate in the guideways 9 within certain limits, so that after the drill 1^a has been projected through the hole 12 in the back plate 1 and between the dies 14 the latter may be closed round the drill 1^a while it is being swaged to the required gage. For the purpose of operating the three movable dies 14 a lever 25 is employed, which is pivotally fixed to the back plate 1 at or in proximity to the bottom thereof. The arm 26 of this lever is pivotally attached to the lower end of a vertically-arranged connecting-rod 27, which rod 27 at its upper end is pivotally attached to the outer end of the lower vertical die-carrier 13. This rod 27 has attached to it a plate 27^a, to which two other connecting-rods 28 29 are pivotally attached, which at their upper ends are connected with the lower arms of two levers 30. These levers 30 work on pins or pivots 31, fitted between lugs 32 at the bottom corners of the plate 8 and the plate 1. The upper arms of these levers 30 are pivotally attached to the die holders or carriers 13 of the two horizontally-reciprocated dies 14. The arms of the levers 30 are formed with slots 33 to allow of the radial movement of the levers 30 about their pins 31, while permitting the die-carriers 13 to move in a rectilinear path in the guideways 9. The several connecting-rods are constructed in two parts formed with right and left hand threads and connected by the adjusting-nuts 34, formed with corresponding right and left hand threads, so that any desired adjustment of said connecting-rods may be effected to bring the several dies 14 into correct relative position to hold the drill 1^a. By moving the outer arm of the lever 25 in a downward direction the several connecting-rods are raised, which forces the bottom vertical die 14 and the two horizontal dies inward round the wings of the drill 1^a. When the lever 25 is moved in the opposite direction, the several connecting-rods are lowered, which move the above-named three dies 14 away from the center and so allow the drill 1^a to be removed. The lever 25, as shown in the drawings, is designed to be operated by means of a hand-wheel 35 and screw 36, working through a boss 37, formed on the outer end of the outer arm of the lever 25. The screw 36 is shown to move about a pivot-pin

38^a, supported in the ears 38 (see Figs. 1 and 2) at the lower end to compensate for the radial movement of the lever 25 about the pivot 39. After the drill 1^a has been placed in position the hand-wheel 35 is operated to force the several dies 14 inward before the 70 swaging of the drill is commenced. Instead of the arrangement shown I may employ a system of levers or other means adapted to operate the several dies more quickly than the hand-wheel 35 and screw 36 previously 75 described.

To the front plate 8 of the machine guides 40 may be bolted, which serve as guideways for the piston 41 or head of the percussive apparatus. This percussive apparatus may be 80 constructed similar to an ordinary percussive rock-drilling machine operated by steam, compressed air, or other motive fluid.

Between the guides 40 for the head of the percussive apparatus and to the front plate 8 85 is bolted or otherwise fixed a horizontal bridle 42, which serves for supporting the dolly or tool 43 for swaging the drill when it is in position between the dies 14 and for forming the cutting edges on the wings thereof. The 90

dolly 43 is shown in detail in Figs. 6 and 7. It is formed with a square shank 44, which works through a hole in the bridle 42. The head of the dolly 43 projects for a short distance between the dies 14. It is capable of 95 moving inward in the parallel portions 19 of the several dies 14. A washer 45 is fitted round the shank 44 at the back of the head, and between the washer 45 and the inside of the bridle 42 is placed a ring 46, of rubber or other resilient material, which rubber ring 46 serves to keep the inner end of the dolly 43 in contact with the extremity of the drill 1^a during the operation of the machine. The shank 44 of the dolly 43, which projects to 100

the front of the bridle 42, is in line with the piston or head 41 of the percussive apparatus and is struck by the latter at each reciprocation. The dolly 43 transmits the blow to the end of the drill 1^a between the several 105 dies 14. The face of the dolly 43 which operates on the drill 1^a is made convex and is formed with four radial V-grooves 47, which form the radial cutting edges longitudinally of the webs or wings of the drill. It will be 115

perceived that by the convex form of the dolly 43 it operates to work out the center portions of the wings toward the tips or outer ends of the wings to bring the drill 1^a up to the gage of the dies 14 or to swage the metal 120 from the center to fill the dies 14. The finished drill is of hollow or concave form, so that the tips of the wings are more prominent or project farther forward than the center of the bit. Thus the metal is located 125 where the greatest wear takes place.

For the purpose of supporting the shank or outer end of the drill while it is being oper-

ated upon by the dolly 43 and between the dies 14 I provide a carriage which is adapted to traverse lengthwise of the table 2. The bed on which the carriage slides is formed by the two angle-irons 48, which are bolted, riveted, or otherwise fixed to the upper edges 5 of the vertical plates or sides 3 4 of the table 2. Between the vertical plates 3 4 and beneath the angle-irons 48 is arranged an inverted channel or U iron 49, which is also riveted or otherwise fixed to the vertical plates 3 4 on the inside. On the top of the inverted channel-iron 49 are arranged two parallel angle-irons 50, which are riveted, 10 bolted, or otherwise fixed to the channel-iron 49 and a strengthening-plate 51 on the inside of the channel-iron 49. Between the vertical members of the angle-irons 50 are fixed a number of transverse pins 52, forming a rack 15 longitudinally of the table 2.

The carriage is comprised of two vertical plates 53, between which plates 53 are placed two blocks 54 at either side of the table 2, to which the plates 53 are bolted or otherwise 20 affixed. The blocks 54 rest on the top of the angle-irons 48, on which they may slide longitudinally of the table 2 in either direction. The vertical plates 53 are shaped at the bottom to project underneath the channel-irons 25 48, (see Fig. 8,) forming the bed for the carriage, so as to prevent the carriage being raised off its bed on the impact of the dolly with the drill. Arranged transversely of the table 2 and journaled in the blocks 54 is a 30 horizontal spindle 55. To retain the spindle 55 in position in the blocks 54, two collars 56 are fixed on the spindle 55 between the blocks 54. On the spindle 55 is fixed a toothed wheel or pinion 57, which engages the pins 35 52, forming the longitudinal rack. One end of the spindle 55 projects beyond the block 54 at one side of the machine and has attached 40 to it a crank 58 for turning the shaft 55 and pinion 57 to move the carriage in either a forward or rearward direction. The two vertical plates 53 of the carriage are formed with 45 semicircular or approximately semicircular recesses which receive and support a heavy cylindrical piece or block 59, which forms the 50 stop to receive the blow when the drill is being operated upon by the dolly 43. The cylindrical piece 59 is shown formed with two annular grooves 60, into which the plates 53 project to afford firm support for the stop. 55 The front of the stop is formed with a recess or hole 61, into which the shank of the drill 1^a is projected.

On the spindle 55 at the side of the table 2 is fixed a ratchet-wheel which is engaged by 60 a pawl operated by a lever 62. The lever 62 is long enough to afford the operator considerable power over the pawl and ratchet-wheel, so that he may keep the pawl in gear with the ratchet-wheel to prevent the back-

ward movement of the carriage when the drill 65 is being operated upon. This ratchet mechanism is provided to prevent the rotation of the spindle 55 and pinion 57 after the carriage has been placed in position to support the 70 drill.

The operation of this machine is as follows: The lever 62 is first raised to disengage the pawl from the ratchet-wheel on the spindle 55, and the spindle 55 is then rotated by the crank 58 to drive the pinion 57 to move the 75 carriage in either a forward or rearward direction, according to the length of the drill to be operated upon. The shank of the drill 1^a is projected into the hole 61 in the front of the block 60. The forward end or wings of 80 the drill (which have been heated) are projected between the dies 14 until the drill abuts the face of the dolly 43. The lever 62 is then lowered to place the pawl in gear with the ratchet-wheel to prevent any movement 85 of the carriage in a rearward direction, and the lever 62 is firmly held in that position. The lever 25 is now operated to move the lower vertical and the two horizontal dies 14 inward round the wings of the drill 1^a, and 90 the percussive apparatus 41 is then brought into operation. The percussive apparatus strikes the dolly 43, which is free to move along the parallel portion 19 of the dies 14 and so swage the drill to the gage of the dies 95 14 or fill up the dies by forcing the metal outward from the center to the ends of the wings. The dolly 43 at the same time forms the cutting edges along the wings of the drill. When the swaging of the drill is completed, the 100 three movable dies 14 are moved outward from the center, the lever 62 is again raised, and the carriage moved backward to allow the drill 1^a to be removed from the machine.

What I claim as my invention, and desire 105 to protect by Letters Patent, is—

1. In apparatus for sharpening rock-drill bits, a main vertical plate, a second vertical plate fixed thereto and having a central aperture and vertical and horizontal guideways radiating from said aperture, die-carriers in said guideways, dies attached to said carriers, a device for adjustably supporting the top vertical die, levers pivoted to the second plate and connected to the horizontal die-carriers, a lever pivoted to the main plate and yieldingly connected with the bottom vertical die-carrier and with the levers operating the horizontal die-carriers, and means for operating the lever pivoted to the main plate. 110 115 120

2. In apparatus for sharpening rock-drill bits, in combination, an upright plate having vertical and horizontal guideways radiating from a central aperture, die-carriers in said guideways, dies attached to the 125 inner ends of said carriers, means for supporting the top vertical die-carrier in position, and means for moving the lower vertical die-

carrier and the horizontal die-carrier toward and away from the central aperture, a dolly projected between the several dies and adapted to reciprocate between the same, means for supporting said dolly in position between the dies, and means for supporting the drill and taking the impact of the dolly on the drill.

In witness whereof I have hereunto set my hand in the presence of two subscribing witnesses.

JOSEPH ADOLPH GEORGE KIRSTEN.
